G. W. SHIPLEY,

ENVELOP,

APPLICATION FILED MAY 2, 1914.

Patented Apr. 13, 1915.

UNITED STATES PATENT OFFICE.

GEORGE WILBUR SHIPLEY, OF ALBEMARLE, NORTH CAROLINA.

ENVELOP.

1,135,064.

Specification of Letters Patent. Patented Apr. 13, 1915.

Application filed May 2, 1914. Serial No. 835,963.

To all whom it may concern:

Be it known that I, GEORGE WILBUR SHIPLEY, a citizen of the United States, residing at Albemarle, in the county of Stanley and State of North Carolina, have invented certain new and useful Improvements in Envelops, of which the following is a specification.

This invention relates to envelops, the primary object of which is to provide an efficient envelop which is manufacturable at a very low cost.

Another object is to prevent tampering with the contents of the envelop without detection, and furthermore to permit the name of the sendee to be visible through the envelop, eliminating the necessity of writing the name and address on the envelop.

Other objects as well as the nature, characteristic features and scope of my invention will be more readily understood from the following description taken in connection with the accompanying drawings and pointed out in the claim forming a part of this specification.

Referring to the drawings: Figure 1 is an envelop constructed in accordance with my invention and shown in a closed position, Fig. 2 is a plan view of the envelop blank, Fig. 3 is a front elevation of a modified form, Fig. 4 is a plan view of the blank envelop, a portion thereof being broken away, and Fig. 5 is a sectional view taken on the line 5—5 of Fig. 3.

In the drawings wherein is illustrated the preferred embodiment of this invention, my improved envelop generally designated 5 in the present instance, comprises a pair of sections 6 and 7, the former of which is the main section and the latter the auxiliary section, said auxiliary section having the marginal sides thereof inclined. An opening 8 is formed in said auxiliary section 7 and has mounted thereover a transparent strip 9, in order that the name of the sendee which is written on the letter in the envelop may be visible therethrough, eliminating the necessity of writing the name of the addressee on the envelop. Flaps 10 extend laterally from the sides of the main section 6, said flaps being preferably inclined, as shown to advantage in Fig. 2, said main section 6 having extending from the upper marginal edge thereof an end flap 11, which has coated thereon an adhesive material 12 in order to facilitate the engaging of the

same with the auxiliary section 7 and the end flaps 10, as shown in Fig. 1.

In the use of the form shown in Figs. 1 and 2 of the drawings, assuming that the envelop is in a blank, as shown in Fig. 2, the laterally extending flaps 10 are first folded upon the main section 6 and the auxiliary section 7, then folded upon the flaps 10 after which the end flap 11 is folded upon the flap 10 and the section 7 and secured thereto through the medium of the adhesive material 12, thereby preventing the displacement of the contents of the envelop, at the same time, providing an efficient and inexpensive envelop which is further provided with the openings 8 for the purpose heretofore described.

The modified form as shown in Figs. 3, 4 and 5, comprises a main section 6' and an auxiliary section 7', the latter being likewise provided with openings, as indicated at 8' over which is engaged a transparent strip 9'. The main section 6' has extending laterally therefrom, flaps 10', while an end flap 11' extends from the upper marginal edge of the main section, thereby providing a blank identical with that shown in Figs. 1 and 2. However, in conjunction with this blank, as shown in Figs. 3, 4 and 5, I have associated a tongue 12' which extends from the free marginal edge of the end flap 11' and engages through an elongated slit 13, the latter being formed in the auxiliary section 7' and adapted for engagement in a pocket formed by extending the auxiliary section 7' and folding it over upon itself, as indicated at 14.

In use this form which we will assume is in a blank, as shown in Fig. 4, has the flaps 10' thereof, first folded upon the main section 6' after which the auxiliary section 7' is folded so as to engage the side flap 10', the end flap 11' then folded upon the auxiliary section 7', the tongue 12' engaging through the slit 13 into the pocket which is provided by extending the ends of the section 7', as indicated on the drawings at 14. By this formation, it is seen that the contents of the envelop cannot be extracted without detection and furthermore, provides a simple and efficient envelop which is manufacturable at a very low cost.

It will be understood that the above description and accompanying drawings comprehend only the general and preferred embodiment of my invention and that various

minor changes in details of construction, proportion and arrangement of parts may be made within the scope of the appended claim and without sacrificing any of the 5 advantages of my invention.

Having thus fully described my invention what I claim as new and desire to secure by Letters Patent is:

An envelop including a blank comprising 10 a main and an auxiliary section, an end and side flap extending from said main section, a pocket formed in the auxiliary section by extending one of the ends thereof and fold-

ing it upon itself, a slit formed in the body of said auxiliary section, and a tongue extending from said end flap for engagement through said flap and into said pocket, adapted for movement therein, whereby the removal of the contents of the envelop, without detection, is prevented.

15 In testimony whereof I affix my signature in presence of two witnesses.

GEORGE WILBUR SHIPLEY.

Witnesses:
